[57] CLAIM

The ornamental design for a storage container for compact discs, CD-ROMs, and discs, as shown and described.

DESCRIPTION

FIG. 1 is a perspective view of a storage container for compact discs, CD-ROMs, and discs showing our new design;

FIG. 2 is a front elevational view thereof;

FIG. 3 is an elevational view of one side thereof, the opposite side being a mirror image thereof;

FIG. 4 is a top plan view thereof;

FIG. 5 is a bottom plan view thereof; and,

FIG. 6 is a rear elevational view thereof.
